UNITED STATES PATENT OFFICE

HENNING HALLSTREAM, OF BROCKTON, MASSACHUSETTS, ASSIGNOR TO CROSS PAPER FEEDER COMPANY, OF BOSTON, MASSACHUSETTS, A CORPORATION OF MASSACHUSETTS

PAPER FEEDING MACHINE

Application filed May 14, 1924. Serial No. 713,233.

The invention relates to paper feeding machines which separate individual sheets from a pile or bank and forward them in succession to a mechanism or machine for operating thereon.

The object of the invention is to provide a sheet separating and feeding mechanism of the suction feed wheel type which is well adapted for high speed operation in separating sheets of any size from a bank or pile and delivering them in regular succession to a folder or other machine for operating upon sheets. To this end the invention comprises the features of construction and combinations of parts hereinafter described and referred to in the claims.

An embodiment of the invention is shown in the accompanying drawings in which Figure 1 is a vertical longitudinal section showing so much of a continuous paper feeding machine as is necessary to illustrate the application of the present invention thereto; and Figure 2 is a partial plan view.

In the drawings the invention is shown embodied in a paper feeder of the "continuous" type in which a bank of feathered or fanned-out sheets is fed from an upper delivery table through a reversing throat and onto a lower feed table, the forward end of which is indicated at 2. The individual sheets are separated from the front end of the bank and presented to continuously acting delivery devices comprising the lower continuously rotating rolls 4 and the upper rolls 6 which are continuously pressed against the lower rolls.

The means for separating individual sheets from the forward end of the bank and feeding them to the delivery rolls comprises a suction feed wheel 8 having its rim perforated to cooperate with an internal suction nozzle 10 in creating a suction through the rim for feeding forward the top sheet. The suction through the rim is controlled by the advancing sheet so that as the forward edge of the sheet reaches a predetermined point, the suction through the rim of the wheel is cut out or stopped and is again re-started as the rear edge of the

sheet passes beyond said point. By thus controlling both the stopping and starting of the suction by the sheet, sheets of any length may be separated and delivered in rapid succession without requiring adjustment or re-timing of the separating mechanism for different lengths of sheets. A mechanism having this general mode of operation is shown and described in application Serial No. 686,528, filed Jan. 16, 1924, and the mechanism of the present application is in the nature of an improvement thereon permitting a more rapid operation and re-setting of the suction controlling devices and consequently a more rapid separation and delivery of the successive sheets.

In the construction shown, the suction nozzle is continuously in active relation to the rim of the suction wheel and the suction through the rim is stopped and re-started by a sheet controlled cut-out valve. For the sake of simplicity in construction and rapidity in operation, the valve is controlled from a sheet operated electric trip finger which makes and breaks an electric circuit to close and open the valve.

As shown, the suction nozzle is in the form of a box adapted to fit snugly against the inner surface of the wheel rim and provided with a series of portholes 12 adapted to register with the rows of perforations 14 which extend substantially from side to side and about the periphery of the rim. The suction wheel is secured to a continuously rotating shaft 16 so mounted that the rim of the wheel is slightly above the forward end of the bank and the nozzle is carried on the end of a hollow arm 18 suitably supported from the transverse bar 20. The arm is connected through a flexible hose 90 pipe 22 with the cut-out valve casing 24, which is in turn connected through the pipe 26 and supply valve 28 with a pipe 30 leading to a suction producing device.

The cut-out valve comprises the inner casing 24 and a rocking sleeve 32 which is provided with slots 36 adapted to be moved by rocking movement of the sleeve into and out of register with a corresponding series of slots 38 formed in that part of the valve 10c

casing which is surrounded by the sleeve. The means for operating the cut-out valve comprises a solenoid magnet 40, the armature 42 of which is connected by a link 44 with an arm 46 projecting upward from the valve sleeve. When the magnet is energized, the valve is rocked into position to shut off communication between the valve casing and the atmosphere so that a suction 10 is produced through the suction nozzle and feed wheel. When the magnet is deenergized, the valve sleeve is moved by a spring 48 into the position indicated in Figure 1 to open communication between the valve casing and the atmosphere, thus cutting out or destroying the suction through the nozzle and feed wheel.

The operation of the magnet and cut-out valve is controlled by a sheet operated 20 switch included in the magnet circuit. As shown, this switch comprises a contact strip 50 carried by a trip finger 52 and a contact pin 54 carried by the block 56 on which the finger 52 is pivoted at 58. The block 56 and 25 trip finger 52 are formed of non-conducting material and the block is secured to a rod 60, which in turn is secured for fore and aft adjustment in a bracket 62. The bracket 62 is secured by a clamping screw 64 to a 30 transverse rod 66 so that it may be adjusted laterally as required. The contact pin 54 is connected by a wire 68 with one of the lead wires from a source of electric current and the contact strip 50 is connected by a wire 70 35 with a binding screw 72, which in turn is connected by a wire 74 with one of the terminals of the magnet 40. The other terminal of the magnet is connected by a wire 76 with one of the terminals of a supply 40 switch 78, the other terminal of which is connected by a wire 80 with the other line wire of the supply circuit.

When no sheet is passing under the trip finger 52, it swings down below the plane 45 of the guide wires 82 and the contact 50 engages the contact 54 completing the magnet circuit so that the cut-out valve is closed and a suction produced through the suction nozzle and wheel. The wheel, therefore, feeds 50 forward the top sheet until its forward edge passes between the delivery rolls and engages the trip finger raising it into the position indicated in Figure 1, and thus disengaging the contact 50 from the contact 54 55 and opening the magnet circuit. The spring 48 then immediately rocks the valve sleeve into the position indicated in Figure 1, opening the exhaust pipe to the atmosphere between the pipe and suction nozzle so 60 that suction through the nozzle and wheel ceases during the delivery of the sheet by the delivery rolls. As the sheet is delivered, the trip finger rides on the top of the sheet and remains in the position indicated 65 in Figure 1. As the rear end of the sheet

passes from beneath the finger, it again drops down, completing the circuit through the magnet which quickly rocks the cut-out valve sleeve into closed position and restores or re-starts the suction through the suction nozzle and feed wheel so that the next sheet is immediately taken by the feed wheel and advanced to the delivery rolls and trip finger. By adjustment of the trip finger toward or from the front end of the bank, the 70 point at which the cut-out operates and the space between the rear edge of one sheet and the front edge of the succeeding sheet 75 may be varied as desired.

The front edges of the sheets at the forward end of the bank rest against and are supported by upwardly supported inclined guide fingers 84 and the upper sheet is raised into engagement with the rim of the wheel by the action of air blasts directed by blower nozzles 86 in an upwardly inclined direction against the front edge of the bank. The air blasts also serve to insure the separation of the top sheet from the sheets beneath it when the top sheet is drawn against the rim of the wheel by the suction therethrough and also serves to wind the top sheet so that it may be readily removed from the bank and carried away by the delivery rolls. The bank of sheets is fed forward over the feed table by the usual feed tapes 88 which are actuated by feed mechanism controlled from the front end of the bank to maintain it in proper relation to the feed wheel as the fanned-out sheets are successively removed. 90

The valve within the supply valve casing 28 which controls the supply of air to the blower nozzles and also the communication between the suction device and the suction nozzle is connected by a link 90 to one arm of a lever 92 which is secured to a transverse rock shaft 94 and the other arm of which is acted on by a spring 96 which tends to rock the shaft in a direction to close the supply valve and thus stop the operation of the machine. The shaft is mounted within a hollow pipe 98 which extends across the machine, and the shaft, when thrown into operating position, as indicated in Fig. 1, is held in this position by suitable latching devices. The end of the shaft is provided with two arms 100 arranged to engage the handle 102 of the supply switch 78 and turn the switch on when the supply valve is moved into operating 110 position and to turn the switch off when the supply valve is moved into position to stop the operation of the machine. 120

While it is preferred to employ the construction and arrangement of parts shown and described in embodying the invention in a feeder of the "continuous" type, this construction and arrangement is not essential to the broader features of the invention and may be varied or modified as found de- 125 130

sirable or best suited to the mode of operation and construction of the feeding mechanism in which it is to be embodied or of the mechanism to which the sheets are to be fed.

What is claimed is:

1. A sheet feeding machine having, in combination, a suction feed wheel having a perforated rim, a suction nozzle within the rim over which it travels, a cut-out valve for reducing the suction through the nozzle, an electro-magnet for operating the valve, and a switch in the magnet circuit operated by the sheet advanced by the wheel.
- 15 2. A sheet feeding machine having, in combination, a suction feed wheel having a perforated rim, a suction nozzle within the rim over which it travels, a cut-out valve for controlling the suction through the nozzle, a spring for holding the valve in position to reduce the suction through the nozzle, an electro-magnet for operating the valve to restore the suction, a trip arranged to ride on the sheet advanced by the wheel, and a switch in the magnet circuit operated by the trip.
- 20 3. A sheet feeding machine having, in combination, a suction feed wheel having a perforated rim, a suction nozzle within the rim over which it travels, a suction conduit connected with the nozzle, a cut-out valve in the conduit comprising a slotted casing forming a part of the conduit, a slotted sleeve surrounding the casing, a spring for holding the sleeve with the slots in register, an electro-magnet, an armature connected with the sleeve and adapted to move the latter in opposition to the spring when the magnet is energized, two contacts in the magnet circuit, and a sheet operated trip carrying one of said contacts.
- 25 4. A sheet feeding machine having, in combination, a suction feed wheel provided with a perforated rim, a suction nozzle within the rim, a suction conduit connected with the nozzle, a cut-out valve having provision for opening the conduit to atmosphere, a spring for normally holding the valve in one position, an electro-magnet, an armature for the electro-magnet connected with the valve and adapted to move the latter in opposition to the spring when the magnet is energized, and a sheet operated trip for controlling energization of the electro-magnet.

In testimony whereof I have signed my name to this specification.

HENNING HALLSTREAM.
